INFANT'S DRESSING TABLE

Lawrence Blazey, Bay Village, David Silverstrom, Lyndhurst, and Elmer Rocker, Shaker Heights, Ohio, assignors to Century Products, Inc., Cleveland, Ohio

Filed Feb. 7, 1972, Ser. No. 224,399

Term of patent 14 years

Int. Cl. D6—03

U.S. Cl. D6—168

FIG. 1 is a perspective view of an infant's dressing table in its extended or open position showing our new design; and

FIG. 2 is a perspective view thereof in closed position with the security strap removed.

The undisclosed side and rear are substantially the same in appearance as the front and side shown, except for the rear central leg which is slightly curved at the bottom in the manner shown by the left and right front legs.

The design is characterized by the retractable top in combination with the stepped exterior sides and the recessed slotted bottom.

We claim:

The ornamental design for an infant's dressing table, substantially as shown and described.
